UNITED STATES PATENT OFFICE.

JOSEPH NUTT, OF DANBURY, CONNECTICUT, ASSIGNOR OF ONE-HALF TO
WM. BECKERLE & CO., OF SAME PLACE.

MACHINE FOR TRIMMING THE EDGE OF HAT-BRIMS.

SPECIFICATION forming part of Letters Patent No. 308,191, dated November 18, 1884.

Application filed July 30, 1884. (No model.)

To all whom it may concern:

Be it known that I, JOSEPH NUTT, of Danbury, in the county of Fairfield and State of Connecticut, have invented a new Improvement in Machines for Trimming Hat-Brims; and I do hereby declare the following, when taken in connection with accompanying nine sheets of drawings and the letters of reference marked thereon, to be a full, clear, and exact description of the same, and which said drawings constitute part of this specification, and represent, in—

Figure 1, a top view; Fig. 2, a side view; Fig. 3, an end view, looking directly toward the rear end of the swinging arm; Fig. 4, a longitudinal sectional view; Fig. 5, a detached view of the wheel W; Fig. 6, a detached view showing the transverse slide for clamping the screw 24 and the slide 32; Fig. 7, a horizontal section 20 showing the manner of communicating rotation to the vertical shaft 9; Fig. 8, a detached view showing the locking mechanism for the cutter-arm; Fig. 9, a top view, the cutter-carriage and clamping-plate removed, also showing the movement of the crank 7 and bars 5 and 3; Fig. 10, a front view of the cutter-carriage—that is, looking from the center outward—enlarged; Fig. 11, a transverse section 30 through the cutter just over the guards, enlarged; Fig. 12, a longitudinal section through the guards, showing the cutter enlarged; Fig. 13, a section through the curl of the brim of the hat, showing section of the guards and cutter, enlarged; Fig. 15, a transverse section 35 through the wedge J, showing a diagram to illustrate the movement of the slides under the action of the wedge, enlarged; Fig. 14, a vertical section through the wedge, showing the intermediate side, 48, on the wedge made 40 adjustable.

This invention relates to an improvement in machines for trimming the edge of hat-brims to give the required elliptical shape, the object of the invention being to construct the machine so that when once set for a given width of brim it will automatically adjust itself to the various sizes of hats, maintaining the standard width of brim; and the invention consists in the combination of mechanism whereby the object of my invention is ac-

complished, as hereinafter described, and more particularly recited in the claims.

A is the base, in the center of which is a tubular standard, B, upon the top of which the clamping device is arranged to hold the hat. This clamping device is of elliptical shape, and consists of a plate, C, made fast to the standard B. Upon the upper face of this plate several horizontal radial slides, D, are arranged so as to work toward and from the center, and as seen in Fig. 1, more or less in number. To each of the slides a spring, E, is applied, the tendency of which is to force the slides inward toward the center. At the outer end the slides are each provided with a horizontal flange, F, and with an upright flange or arm, G, resting upon the several flanges F, and surrounding the several upright flanges G is a flat thin metal band, H, greater in length than the extreme circumference to which the slides may be thrown out, the two ends of the band overlapping each other, as seen in Fig. 1, and so that as the slides are thrown out the band will yield to the increased circumference thus produced. 75

Through the standard B is a vertical spindle, I, its upper end terminating in an inverted-frustum-of-cone-shaped wedge, J. This spindle is arranged for vertical movement, so that it may be drawn down into the standard 80 or raised therefrom, as occasion may require. This may be done by a foot-pedal attached to it, or otherwise. The wedge J is best made with a number of sides equal to the number of slides, and so that the inner end of each 85 slide will abut against a corresponding side of the wedge J, as seen in Fig. 4. As the spindle is drawn down, the wedge J moves with it, and because of its conical or wedge-like shape it strikes the inner end of the slides and forces 90 them outward, according to the extent to which the wedge is drawn downward, and such forcing outward of the slides correspondingly expands the band H and increases its circumference. 95

The hat to be trimmed is placed over the clamping device until its brim rests upon the flanges F, and when so resting the wedge J is drawn downward until the band H is expanded to give a firm bearing upon the inside of 100

the crown, and so as to give the proper elliptical shape to the crown.

In order that the hat may be held so as to prevent its slipping upon the band H, a pin, 5 K, is arranged at some point on the band H, so as to pierce the crown of the hat, and thereby retain it in its proper relation upon the clamping device, and so that the position, once fixed, cannot be changed. The hat is held up 10 on the clamping device by the depressed wedge, and is relieved therefrom by permitting the wedge J to rise, and when the wedge is so raised the reaction of the springs E, which were compressed by the descent of the wedge, 15 will return the respective slides D to their contracted position, and so as to permit the removal of the hat.

It will be understood that in the contracted or normal position of the slides the clamping 20 device is of smaller circumference than the smallest hat to be trimmed.

Upon the central standard, B, an arm, L, is hung, and so as to turn upon the standard as its center of motion, and so as to be revolved 25 in a horizontal plane around the said standard. On the top of the arm L, and in a plane parallel with the hat clamp, a slide, M, is arranged between guides N, and so as to be moved back and forth in a radial line with relation to the 30 center of the standard—that is, toward and from the center. Upon the top of the slide M is the cutter-carriage O, hung upon a pivot, P, and so as to turn upon said pivot in a horizontal plane independent of the slide M, but 35 so as to partake of whatever radial movement may be imparted to the slide M. The radial movement of the slide M is for the purpose of moving the cutter in an elliptical path around the hat, that it may trim the edge of the brim 40 in accordance with such elliptical path. Upon the base is a circular track, R, concentric with the standard. The upper surface of this track is curved, say starting from the point S, Fig. 3, and which is a point in line with the longer axis of the ellipse. The track 45 rises one-fourth of the circle—say to the point T, Fig. 2, which is in line with the shorter diameter of the ellipse, the distance from the lower point, S, to the higher point, T, being 50 one-fourth of the circumference of the circle of the track. From this point or line of the shorter diameter the track descends to the point U, which is opposite the point S and in the same plane, making the second quarter. 55 From this point U the track rises to the point V, which is in the same plane with the opposite point, T, and completes the third quarter, then descends to the point S, or place of beginning, the rise and fall of the respective quarters being the same. Within the arm L is a 60 wheel, W, hung upon an axis, a, and so that the wheel revolves in a vertical plane, the axis being at right angles to the radius from the center of the standard. The wheel is shown 65 detached in Fig. 5. In the wheel W are two radial slots, b b, diametrically opposite each

other. In one of these slots is a nut, c, and in the other a nut, d. One of the nuts is threaded right hand and the other left hand, and arranged so as to move like slides in their 70 respective slots b. Diametrically through the wheel and through the nuts c d is a screw, e, one end threaded right hand and the other left hand, corresponding to the two nuts, and so that the screw turned in one direction will 75 draw the nuts together, or in the opposite direction will force them asunder. At right angles to the slots b b is a third slot, f, in which a slide, g, is arranged. The slide g is connected to the nuts c d by links h, hinged by one end 80 to the respective nuts, the other end of the two hinged to the slide g, and so that as the nuts c d are drawn together the slide g will be forced outward, or vice versa. On the nut c is a stud, i, which extends to the right and 85 left outside the surface of the wheel.

1 is a follower arranged inside the arm L, and so as to extend up each side of the wheel W. In the respective sides of the follower is a horizontal slot, m, in which the studs i on 90 the nut c stand. The follower 1 is arranged to ride upon the circular track R. The studs i make connection between the wheel W and the follower 1, so that as the follower rises it will impart rotation to the wheel W, or vice 95 versa. Therefore, starting from the lowest point in the track, if the arm be turned, the follower 1 will ride upon the track to the highest point T, turning the wheel W in the direction indicated by the arrow in Fig. 4. Descending from the point T to U, the wheel will be returned. The slide g in the slot f has upon it a stud, n, which works between a pair of arms, o o, extending down from the slide M, as seen in Fig. 4, and so that as the wheel W 100 rotates, as before described, it will impart a corresponding longitudinal movement to the slide M—that is to say, as the follower rides up one incline it will force the slide forward, and as it rides down on the opposite side will 105 move the slide M rearward. This back-and-forth movement of the slide, combined with its circular movement around the center, will cause a given point on the slide to describe an ellipse about the center, and that ellipse will 110 vary according to the position of the studs i and n—that is to say, if the stud i be moved nearer the center of the wheel, then the up-and-down movement of the follower will give a greater extent of movement to the wheel, 115 and so the stud n, if it be moved outward from the center, will impart to the slide a greater extent of movement, or vice versa, and this extent of movement is varied by turning the screw e, and which operates to throw the stud 120 n outward as it carries the stud i inward, or vice versa.

To insure the rear movement of the slide as the follower 1 passes down the incline, the slide is constructed with two rods, p p, one at 125 each side, and extending forward through bearings r on the hub of the arm L, and upon these 130

rods a spring, *s*, is arranged to be compressed as the slide moves forward, and so that the reaction will tend to force the slide backward.

As before stated, the cutter-carriage *O* is hung upon a pivot, *P*, on the slide *M*. This pivot *P* is itself made adjustable in the slide, as and for the purpose hereinafter described.

2 is the cutter arranged on the cutter-carriage, and so as to cut around the brim of the hat in the elliptical path defined by the follower 1 passing over the circular track, as before described. Were the cutter-carriage stationary on the slide *M*, the plane of the cutter with relation to the brim would be constantly changing from its starting-point—say at the longer diameter—until it reached the first quarter-point—that is to say, if the cutter stood in a plane at right angles to the radius of this longer diameter, that angle would change as it advanced toward the next quarter-point, where it would again assume the position of right angle to the radius.

It is necessary, in order that the cutter shall work smoothly, that it maintain always the same angle with relation to the radius of the ellipse it is cutting, and therefore should change its plane through each quarter of the circumference cut. To give to the cutter such an automatic adjustment, a bar, 3, extends along the top of the slide *M*, and through a corresponding groove in the bottom of the carriage *O* this bar extends toward the center of the machine and beneath the clamping-plate. Transversely across the arm and in guides 4 4 a horizontal sliding bar, 5, is arranged, to which the forward end of the bar 3 is hung, as seen in Fig. 9. The bar 5 is constructed with a slot, 6, at right angles to it, in which plays a crank-pin, 7. This crank-pin is on the head 8 of a vertical shaft, 9, arranged in bearings 10, and so that the crank revolves in a horizontal plane. The vertical shaft is caused to rotate by means of a fixed gear, 11, on the standard *B*. (See Fig. 7.) The vertical shaft 9 is provided at its lower end with a pinion, 12, and between the pinion 12 and the fixed gear 11 is an intermediate pinion, 13, the two pinions being arranged upon the arm *L*, and so as to travel with it around the upright. In such rotation 50 of the arm around the upright rotation is imparted to the vertical shaft 9, and the gears are in such relation to each other, as shown, that at each full rotation of the arm around the upright two full revolutions are communicated to the vertical shaft 9. In such revolution of the vertical shaft 9 the crank-pin 7 travels in the slot 6, and imparts two full reciprocating movements to the bar 5 at right angles to the slide *M*, which carries the cutter-carriage. This reciprocating movement of the bar 5 through the bar 3 imparts a corresponding rocking movement to the cutter-carriage, which turns upon its pivot *P*. The cutting-point of the cutter 2 stands substantially over the center of the pivot *P*, as seen in Fig. 4. The rocking movement imparted

to the cutter-carriage through the sliding bar 5 causes the cutter to constantly turn with relation to the radius of the arm *L* during each fourth of its revolution. Standing at the longer diameter, as seen in Fig. 1, the bar 3 is parallel with the longer diameter of the ellipse to be cut, and also parallel with the slide *M*. At this time the crank-pin 7 stands at the point of one-half its throw. As the cutter is moved from this point, say in the direction indicated by the arrow, Fig. 1, the crank-pin 7 turns in the opposite direction, as indicated by the arrow, and throws the sliding bar 5 inward to the extent of one-fourth of the travel of the crank, as indicated in broken lines, Fig. 9. This extreme throw occurs at a point midway between the starting-point and the end of the first quarter or point, *T*, as indicated in broken lines, Fig. 9. Continuing from this point, the throw of the crank returns the bar 3 and the cutter-carriage until, arrived at the quarter-point *T*, the carriage is again returned into its position parallel with the arm *L*, and then presents the cutter at right angles to the shorter diameter. During the next quarter the throw of the crank is completed, and brings the cutter again in the same relation to the longer diameter when it has reached the opposite point, *U*, from which it started. Continuing the rotation around the circle, the crank performs another full revolution and correspondingly turns the cutter-carriage, and by thus turning maintains the cutter always in the same relation to the line it is cutting.

In illustrating the invention I show the cutter as arranged for cutting the inner edge of a curled brim. The cutter is supported on an arm, 14, hung upon the cutter-carriage upon a shaft, 15, at right angles to the longitudinal central line of the carriage. In the forward end of this arm is a vertical spindle, 16, carrying a guard, 17. This spindle is arranged to be turned by means of a handle, 18, and is provided with a spring, 19, the tendency of which is to turn the guard toward the cutter. This guard, when in operation, stands inside the curl of the brim, as seen in Fig. 13, and so as to work upon the under side of the curl, as a support for the curl of the brim against the cut.

20 is a second guard, arranged to slide vertically in the arm 14, depressed by a spring, 21. This second guard bears upon the upper side of the curl and surrounds the cutter, as seen in Figs. 11 and 12, and so as, with the guard 17, to form a firm support for the brim at the point of cutting. The arm 14, which carries the cutter and the guards, may be turned upward upon its shaft 15, as seen in broken lines, Fig. 4, for conveniently introducing the hat, as well as for the examination of the cutter and guards when occasion requires. As the sizes of hats vary, it follows that the cutter must be adjustable to adapt it to such variation of sizes. To admit of such adjustment the pivot *P* is made as a part of a slide, 22,

arranged in a longitudinal slot, 23, in the slide M, as seen in Fig. 9, and so that the pivot, with the cutter-carriage, may be moved longitudinally on the slide M to set the cutter nearer to or farther from the center of motion, as occasion requires.

Longitudinally in the slide M is a screw, 24, which works through a nut, 25, in the pivot-slide 22. The nut carries a trunnion, 26, upon its upper end, on which is hung a longitudinally-toothed rack, 27, which lies over upon the top of the slide M, as seen in Fig. 9, and passes through the pivot. The cutter-carriage has a longitudinal groove upon its under side, corresponding to the rack 27, and in which the rack stands, but so that it may be moved independent of the cutter-carriage. A shoulder, 28, on the nut comes to a bearing against a corresponding shoulder in the slide 22 when the rack has been drawn back to its extreme position with relation to the pivot, and at this time the trunnion 26 is concentric with the pivot, as seen in Figs. 4 and 9.

Made fast to the shaft 15, on which the cutter-arm 14 is hung, is a toothed segment, 29, which works into the teeth in the rack 27, as seen in Fig. 4, and so that when the arm 14 is turned upward, as seen in broken lines, Fig. 4, the rack 27 will be forced forward, as seen in broken lines, Fig. 4, carrying with it the screw 24. The forward end, 30, of the screw 24 is arranged to pass through a corresponding hole, 31, in the standard, and so as to enter the vertical space within which the spindle I is arranged, and as seen in broken lines, Fig. 4. From the slide 22 a spindle, 32, extends rearward parallel with the screw 24, and in the same plane, as seen in Fig. 6. In rear of the slot 23 in the slide N is a transverse slide, 33, which carries on one side a half-nut, 34. This slide is operated by a screw, 35, arranged in the slide M, and extending through a slot, 36, in the side of the guide, as seen in Fig. 2, provided with a head, 37, upon the outside, by which it may be turned, and so that by turning the screw in one direction the half-nut is brought to bear upon the screw 24, to engage it or clamp it to prevent its rotation, or disengaged to leave the screw entirely free, as the case may be. The screw 35, when turned inward to its extreme point, and when the half-nut is entirely disengaged from the screw 23, clamps upon the spindle 32, so as to hold the slide 22 in firm engagement with the slide M.

The operation of this adjusting mechanism is as follows: Suppose the machine, as seen in Fig. 4, to be set for a brim of a certain width—that is, so that the cutter stands at a certain determined distance from the periphery of the clamping device at the longest diameter. Now, if in this position the cutter-arm be raised to its extreme up position, as seen in broken lines, Fig. 4, such movement of the cutter-arm will force the screw 24 forward until its extreme end 30 comes in contact with the spin-

dle in the standard, as seen in broken lines. That side of the standard toward the spindle, when at this longest diameter and starting-point, presents a surface, 38, inclined toward the cutter upon the same inclination as the wedge J. The hat is placed upon the clamping device while the cutter is thus raised and the screw 24 in its extreme forward position to clamp the hat, as before described. The spindle I is drawn downward to force the wedge J between the inner ends of the slides on the clamp until the clamps come to a bearing inside the hat. As the wedge thus passes downward, the incline 38 will act upon the end 30 of the screw 24, as it does upon the clamps, and force the screw to retire to the same extent that the clamp on the longest diameter is forced toward the cutter, and such retreating movement of the screw will be imparted to the cutter-carriage, the cutter-arm being still held in its up position, and when the hat is properly clamped the descent of the spindle ceases. Then the cutter-arm is turned downward, and the cutter will be presented to the brim the same distance from the crown of the hat that it was at first, and will there trim the edge of the brim. The brim trimmed, the spindle I rises to permit the return of the clamps. Then the hat is removed, and the cutter-arm is again raised to bring the screw forward until its end 30 strikes the inclined face 38, as before. Then a second hat is placed upon the clamping device and clamped by the descent of the spindle I, as before. If this second hat be smaller or of less diameter than the previous hat, then the spindle I descends to a less distance; consequently the cutter-carriage is moved a correspondingly less distance from the center; but it is moved to the same extent that the clamps are moved, and so that when it is turned down for cutting it will stand the same distance from the crown for the second and smaller hat that it did from the crown of the first or larger hat. The cutter-arm is locked in both its up and down position by means of a bolt, 39, hung to one arm of a lever, 40, the other arm forming a thumb-piece, 41, by which the bolt may be drawn, the spring 42 serving to throw the bolt inward. The bolt is arranged to enter a hole, 43, in the segment 29 when the cutter-arm is turned downward, or 44 when the arm is turned upward. This locking is necessary, in order that the rear movement of the rack through the screw 24 may be prevented from turning the cutter-arm segment 29 upon its center, and so that the carriage, segment, and arm may move rearward together. When the hat is properly clamped by the forcing down of the spindle I, and the screw 24 has been moved to its extreme rear position, it is there clamped by turning the screw 35 to bring the clamping-nut 34 into firm engagement with the screw, and so that the cutter-carriage may be firmly held during the operation of cutting. As soon as one brim has been trimmed, and before the cutter-arm

can be raised, the clamp upon the screw 24 is released by returning the screw 35 until the screw is entirely free from its clamp. In releasing the screw 24 from its clamp 34, the inward movement of the screw 35 brings it to a bearing upon the spindle 32, and so that the slide 22 will be clamped in its place to prevent movement or disadjustment of the pivot P, which would be likely to occur in turning 10 the cutter-arm upward.

To adjust the machine for a different width of brim, the screw 24 is employed. Suppose it to be for a narrower brim than that which I have described as being cut. The screw 24 is 15 then turned backward to bring its end 30 nearer the nut 28, and as the end 30 of the screw fixes the position of the cutter with relation to the clamping device or crown of the hat, it follows that if the end 30 of the screw be moved 20 nearer to the nut 28 when the end 30 strikes the incline 38 on the spindle the cutter will be as much nearer the periphery of the clamping device as the end of the screw has approached the nut; or if it be for a broader 25 brim, then the screw 24 is turned inward to take its end 30 farther from the nut. The result of this last adjustment is that when the end 30 of the screw strikes the incline 38 on the spindle the cutter will be farther from the periphery 30 of the clamping device. The width to be cut is determined by the distance which the cutter stands from the clamping device in its normal condition. To set the cutter, therefore, its carriage and the screw 24 are released 35 from the clamping of the screw 35. Then, while the cutter-arm is still down, as seen in Fig. 4, the cutter-carriage is moved forward until the cutter is brought to its proper or desired relation to the periphery of the clamping 40 device, and when that point is reached the carriage is clamped, as before, the cutter-arm turned upward to its extreme position and locked, then the screw 24 turned inward until it comes to a bearing against the incline 38 45 on the spindle, as seen in broken lines, Fig. 4. This done, the work proceeds as before described.

The track over which the follower 1 works is made in segments, which may be changed 50 for other segments giving a greater or less rise to vary the extent of the ellipse.

The illustration of the cutter to cut the inner edge of the curl of the brim will be sufficient to enable those skilled in the art to adapt 55 the cutter to cutting the edge of a flat brim, it only being necessary to change or adjust the guards and cutter accordingly, and as in machines usually employed for trimming hat-brims.

60 The crank-pin 7 may be adjustable by a leading-screw, as seen in Fig. 1, or otherwise, and so that the extent of movement of the bar 5 may be varied to adjust the outline of the cutter as the ellipse which it is to cut is 65 changed.

I have described the cutter as working at

right angles to the radius of the ellipse; but a slight inclination from that position one way or the other may be desirable, according to the work being performed. Such adjustment of 70 the cutter may be made by turning it in its socket or holder and resetting it when in the desired position.

I have represented the device carrying the nuts c d and the slide g for moving the slide 75 M as a wheel, and prefer to make that device in wheel shape; yet it will be evident that the portions of the wheel not necessary for guiding the nuts and the slide may be cut away. Therefore by the term "wheel" I wish to be 80 understood as embracing any shaped device which may be applied to so support and carry the nuts and slide.

The adjusting-screw 24 may be dispensed with where a constant breadth of brim only is 85 required, and in such construction the end 30 may be considered as made as a continuation or permanent part of the rack 27.

Instead of the devices which I have shown and described to give to the cutter-carriage its elliptical path, the mechanism employed in other hat-trimming machines to give such elliptical path to the cutter may be employed. I therefore do not wish to be understood as limiting my entire invention to the peculiar devices by 95 which the elliptical path is produced.

In making up the elliptical clamp it is necessary that all the slides should move toward one common center, in order that they may be acted upon by the wedge J. The point in the 100 circumference of the clamping device at both the longest and shortest diameters is at substantially right angles to the radius at those points, as seen in Fig. 15, 39 representing the longer radius, and 40 the shorter radius. The 105 intermediate slide springs from the center and on the radius 41; but because of the elliptical shape of the clamp it will be observed that at the point where the radius 41 crosses the circumference the radial line is oblique to the circumference, instead of at right angles, as at 39 and 40. The movement under the action of the wedge is alike in all directions, and may be illustrated by two circles, 42 and 43. Now, if the slide on the radius 41 be only moved to 110 the same extent as the slide on the radius 39 or 40, the distance between the two ellipses at that point will be as from 44 to 45, and because that radius is oblique to the circumference those two points will be nearer together than are the same points on the radius 115 39 or 40 by so much as the obliquity of the radius to the circumference.

In order to make the circumference of the ellipses parallel to each other, the distance between the two circumferences at 44 should be as from 44 to 46—that is, a line at right angles to the circumference the same length as between the two circumferences on the radius 39 and 40. In order to make the circumference parallel 120 throughout, it is therefore necessary to give to the slides intermediate between the longer and 125

shorter diameter a greater throw than that given to the slides on said longer and shorter diameters—say as from 44 to 47. To accomplish this object in the clamp, I construct the 5 sides 48 of the wedge intermediate between the sides which operate upon the slides at the longer and shorter diameter in separate pieces, as seen in Figs. 14 and 15, and so that they may be adjusted and set to a greater or less 10 projection, as may be required to adapt them to various-shaped ellipses. These sides are set into a seat, 49, at their lower end, and are embraced by a cap, 50, at the top, held by a nut, 51, the cap overlapping the upper ends 15 of the adjustable sides 48 to hold them in their place, and they are adjusted by screws 52 at the back of each piece, or any equivalent therefor.

I claim—

20 1. In a machine for trimming hat-brims, the combination of a clamping device of elliptical shape, arranged to clamp the hat upon the inside of its crown, a circular track concentric with said clamping device, the upper surface 25 of said track lowest in the plane of the longest diameter of the clamping device gradually rising from said lowest point to the quarter-points or plane of the shortest diameter of the clamping device, an arm, L, arranged to swing over 30 and concentric with said circular track, a follower, 1, arranged in said arm to ride upon said track, a wheel, W, in said arm, arranged to receive a rotary movement in a plane parallel with the axis upon which the arm swings, 35 a slide arranged upon said arm and movable in radial guides in a plane at right angles to the axis on which the arm turns, and carrying a cutter, the said follower constructed to engage said wheel W at one side of its axis, and 40 the wheel W constructed to engage said slide at right angles to its engagement with said follower, and whereby as the follower passes over said track a backward and forward movement will be imparted to said slide and cutter, substantially as described.

45 2. The combination of a clamping device of elliptical shape, arranged to clamp the hat upon the inside of its crown, the arm arranged to swing around said clamping device in a plane 50 parallel therewith and upon an axis concentric thereto, the slide M, arranged upon said arm, the cutter-carriage O, hung upon a pivot, P, on said slide, the bar 5, arranged transversely across said arm, the bar 3 in connection with the cutter-carriage, one end hung to said bar 5, the fixed gear 11 upon the axis of the clamping device, the vertical shaft 9 on said arm, and arranged to receive two full revolutions from said gear 11 to one revolution of 55 the arm L, the said shaft carrying a crank, 7, in connection with said bar 5, substantially as described.

60 3. The combination of a clamping device of elliptical shape, arranged to clamp the hat upon the inside of its crown, the arm L, arranged to swing around said clamping device

in a plane parallel therewith, a circular track below said arm and concentric with the axis upon which it swings, the upper surface of said track lowest in the plane of the longest 70 diameter of the clamping device gradually rising from said lowest point to the quarter-point or plane of the shortest diameter of the clamping device, a slide arranged upon said arm and movable in radial guides in a plane 75 at right angles to the axis on which the arm turns, and carrying a cutter, the wheel W in said arm arranged to receive a rotary movement in a plane parallel with the axis upon which the arm swings, adjustable nuts c d 80 in said wheel, slide g, also arranged in said wheel and connected to said nuts, follower 1, arranged in said arm to ride upon said track and connected to one of said nuts, whereby a rotative movement is imparted to said wheel 85 as the follower rides over the inclines on the track, the slide g connected to the slide M, and whereby the rotative movement of the wheel imparts reciprocating movement to the said slide, substantially as described.

90 4. The combination of a clamping device of elliptical shape, arranged to clamp the hat upon the inside of its crown, the arm L, arranged to swing around said clamping device in a plane parallel therewith and upon an axis 95 concentric thereto, the slide M, arranged upon said arm in a plane parallel with the plane of said clamping device, mechanism, substantially such as described, to impart a reciprocating movement to said slide toward and from the axis upon which the arm swings, the slide 22, arranged longitudinally in said slide M, and carrying the pivot P, the cutter-carriage hung to said pivot, mechanism, substantially such as described, to impart a rocking movement to said carriage in a plane parallel with the slide upon which it is pivoted, the nut 25 in said slide 22, the longitudinal screw 24 through said nut, and whereby the cutter-carriage may be moved toward or from 100 the clamping device, substantially as described.

105 5. The combination of a clamping device of elliptical shape, arranged to clamp the hat upon the inside of its crown, the arm L, arranged to swing around said clamping device in a plane parallel therewith and upon an axis 110 concentric thereto, the slide M, arranged upon said arm in a plane parallel with the plane of said clamping device, mechanism, substantially 115 such as described, to impart reciprocating movement to said slide toward or from the clamping device, the slide 22, arranged longitudinally in the slide M, nut 25, screw 24, toothed rack 27, the cutter-carriage pivoted 120 to said slide 22, mechanism, substantially such as described, to impart a rocking movement to said carriage in a plane parallel with the slide upon which it is pivoted, cutter-arm 14, 125 hung upon said cutter-carriage, and carrying the toothed segment 29, arranged to work in said rack 27, with the clamping-spindle I, con-

structed with the incline 38, substantially as and for the purpose described.

6. The combination of a clamping device of elliptical shape to clamp the hat upon the inside of its crown, the arm L, arranged to swing around said clamping device and in a plane parallel therewith and upon an axis concentric thereto, a slide arranged upon said arm in a plane parallel with said clamping device, mechanism, substantially such as described, to impart reciprocating movement to said slide M toward and from said clamping device, the slide 22, arranged longitudinally in said slide M, provided with its spindle 32, the nut 25, screw 24, parallel with said spindle 32, the transverse slide 33, its adjusting-screw 35, the said slide 33 constructed with a half-nut clamp, 34, and with a bearing-surface to engage the spindle 32, the cutter-carriage O, hung upon a pivot on said slide 22, mechanism, substantially such as described, to impart a rocking movement to said carriage in a plane parallel with the slide upon which it is pivoted, the cutter-arm hung to said carriage and carrying the segment 29, substantially as and for the purpose described.

7. The combination of a clamping device of elliptical shape, arranged to clamp the hat upon the inside of its crown, the arm L, arranged to swing around said clamping device in a plane parallel therewith and upon an axis concentric thereto, the slide M, slide 22, longitudinally arranged in said slide M, cutter-carriage O, hung upon a pivot upon said slide 22, mechanism, substantially such as described, to impart a rocking movement to said cutter-carriage, rack 27, arranged longitudinally in said cutter-carriage, cutter-arm 14, hung upon said carriage and carrying a toothed segment,

29, with the spindle I, constructed with the incline 38, substantially as described.

8. In a machine for trimming hat-brims, the combination of a clamping device of elliptical shape, arranged to clamp the hat upon the inside of its crown, a cutter-carriage arranged to swing around said clamping device in a plane parallel therewith and in an elliptical path, a toothed rack arranged longitudinally in said cutter-carriage, with an extension therefrom toward the center of motion, the cutter-arm hung to said carriage, carrying a toothed segment to work into said toothed rack, the central spindle, I, by which the clamping device is forced into engagement with the crown of the hat, said spindle constructed with an incline, 38, against which the extension from the rack may strike, substantially as and for the purpose described.

9. In a machine for trimming hat-brims, the herein-described clamp, consisting of the combination of a plate, slides arranged thereon in guides parallel with the plane of the plate, and so as to be moved outward and inward in lines radiating from the center of the ellipse, the wedge arranged to be moved up and down through said plate, and with sides corresponding to each of said slides, and whereby said slides will be forced outward or permitted to retreat, according to the movement of the wedge, the sides of the wedge intermediate between the slides on the longest and shortest diameters made adjustable, substantially as and for the purpose described.

JOSEPH NUTT.
